UNITED STATES PATENT OFFICE.

DONALD M. MARTIN, OF WINTHROP, MASSACHUSETTS.

SCAFFOLD BRACKET.

Application filed May 9, 1919. Serial No. 295,870.

To all whom it may concern:

Be it known that I, DONALD M. MARTIN, a subject of Great Britain, residing at Winthrop, in the county of Suffolk and 5 State of Massachusetts, have invented certain new and useful Improvements in Scaffold Brackets, of which the following is a specification.

This invention relates, generally, to brackets and has reference, more particularly, to a novel construction of scaffold-bracket for use in any form of scaffolding, such as is employed by painters, builders, etc.

The improved bracket is of special utility 10 in connection with the construction of stucco houses.

The present invention has for its principal object to provide a bracket, which is readily attachable to an upright or other 20 part of a scaffolding of the usual form and easily detachable therefrom, affording an attachment, without the use of nails, screws, and the like, which combines an economy in construction and manipulation, facility 25 and efficiency of operation, and strength and durability unattainable by devices involving the use of the complex and cumbersome wood-engaging means heretofore employed.

These and other objects not at this time 30 more particularly enumerated will be more clearly understood from the following more detailed description illustrated by the accompanying drawings showing the preferred form of the invention in which—

Fig. 1 is a front view showing the bracket of the invention mounted upon an upright of a scaffold. Fig. 2 is a plan view showing the bracket detached from the upright and partially collapsed. Fig. 3 is a section taken 40 along the line $x-x$ in Fig. 1. Fig. 4 is a section taken along the line $y-y$ in Fig. 1. Fig. 5 is a section taken along the line $z-z$ in Fig. 1. Fig. 6 is a fragmentary view showing the construction of the wood-engaging end of one of the bracing elements 45 shown in Fig. 1 and Fig. 2.

Similar numerals refer to similar parts throughout the several views.

The bracket consists, in the preferred 50 form, of the angle-iron 2 forming the main beam, the pair of angle-irons 3 forming the arms, the pair of angle-irons 4 forming the struts for the purpose of bracing the arms, and the locking and tightening device more 55 particularly shown in Fig. 4. 1 is an upright of an ordinary scaffold.

The pivotal connections employed render the device collapsible, a feature which not only facilitates its attachment, and detachment, but also enables it to be folded into 60 a compact form convenient for storage and transportation.

Fig. 2 shows the device partially collapsed, and by particular reference to this drawing the general organization of the invention 65 may be readily seen. 2 is the main beam pivotally supporting the arms 3 at 6. The arms 3 are provided with object-engaging means. The specific means shown are spurs 8 integral with the ends 7 of the arms 3. 70 The spurs are adapted to engage the wood of the upright 1. The stops 9 integral with the main beam 2 are adapted to engage the slots 10 in the arms 3. The lugs d serve as guards to retain the flooring in position. 75

The struts or bracing elements 4 are pivotally connected with the arms 3 at 11, and each is provided with a spur 12 integral with the end 13 adapted to engage the wood of the upright 1, and with a stop 21. 80

The bracket is brought into its operative position by swinging the arms 3 into perfect alignment with the main beam 2 as shown in Fig. 1. The arms 3 act by leverage with the pivotal connections 6 as fulcrums, and the pressure thereby exerted in effecting the alignment brings the spurs 8 into biting engagement with the wood of the upright 1. The biting engagement when fully effected is shown by the dotted lines 85 in Fig. 1, while Fig. 3 shows in cross-section the upright 1 deeply engaged by the spurs 8. The stops 9 engaging the slots 10 as shown in Fig. 5 lock the arms into the alignment effected as above, while the positioning of the main beam 2 in said alignment prevents lateral sagging of the arms 3. 90

The locking and tightening device consists of the bolt 5 with the threaded end 20 and the headed end 14 by which it pivotally 100 engages at 15 the right-hand strut as shown in Figs. 1, 2, and 4. 16 is a wing-nut engaging the threaded end of said bolt 5, and 17 is a collar slidably mounted on the same provided with a stop-lug 18. When the struts 4 are swung into operative position with the spurs 12 engaging the wood of the upright 1 at 19 as shown in Fig. 1, the stop-lug 18 is brought into engagement with the slot 22 in the left-hand strut 4, the struts 110 4 are locked in this position by turning the wing-nut 16 as shown in Fig. 1, and by

further turning this nut a biting engagement of the spurs 12 is effected to any extent desired as shown in Fig. 4. The pressure transmitted through the struts as by 5 walking on the platform supported by the brackets increases said biting engagement, and the pressure-plates 21 act as stops to prevent the spurs being driven too deeply into the wood by this pressure, an unusual 10 pressure on one arm tending to drive the spur more deeply into the upright, then a like pressure on the other arm tending to drive the corresponding spur into the said upright, as the thrusts of the two arms oppose each other the result would be that the former spur would be partially withdrawn thereby loosening its grip on said upright.

It will be obvious that this invention has 20 a unique adaptability to the exigencies of practical use, an entirely effective form of the device weighing but a few pounds, while measuring up to the most exacting tests for strength. Its novel features give it a special 25 adaptability to the scaffolding used in the construction of stucco houses. Heretofore in this construction the flooring has been laid on brackets formed by nailing light pieces of lumber directly to the uprights. The laying of each additional strip of stucco 30 necessitates an additional row of brackets so that the laying of the first complete coat of stucco leaves the entire wall lined with rows of brackets which have to remain until the succeeding coats have been laid. 35 The lumber employed for this purpose cannot be removed to make new brackets without splitting.

All this inconvenience and waste are obviated 40 by the use of the present invention. A single working row of brackets is sufficient, it being only necessary when a strip of stucco has been laid to swing another row of brackets into position and lay the flooring 45 from the former row thereon.

While it is preferred to employ the specific 50 construction and arrangement of the parts shown and described, since this construction and arrangement are the simplest and most efficient embodiment of the invention which has been yet devised, it will be understood 55 that this construction and arrangement are not essential except so far as they are specified in the claims and may be varied or modified without departing from the broader features of the invention.

I claim:

1. In a scaffold bracket a main beam, two 60 oppositely extending supporting arms pivoted thereto so as to contact with a scaffold bracket on opposite sides with each arm engaging said upright so that the thrust of each of said arms is taken up by the thrust of the other arm when the arms are swung into operative position, a pair of struts pivotedly connected therewith, each strut being

provided with a spur adapted to form a biting contact with the scaffold upright and means for firmly effecting said contact with said scaffold upright.

2. A scaffold-bracket comprising a main beam, a pair of arms pivotally connected therewith and provided with object-engaging means, said arms being movable into alignment with said main beam so as to effect a biting engagement with the wood of a scaffold upright by the leverage engendered by such movement, a pair of struts pivotally connected with said arms and adapted to furnish bracing support for the same, the free ends of said struts being each provided with wood-engaging means and a stop, and means for connecting said struts, locking them in position in engagement with a scaffold-upright, and exerting pressure to effect a biting engagement with the wood of said upright.

3. A scaffold-bracket comprising a main beam, a pair of arms pivotally connected therewith and provided with object-engaging means, said arms being movable into alignment with said main beam so as to effect a biting engagement with the wood of a scaffold-upright, and means for furnishing bracing support for said arms.

4. A scaffold-bracket comprising a main beam provided with stops, a pair of arms pivotally connected with said main beam, provided with slots adapted for engagement by said stops, and having their inner ends terminating in wood-engaging means, a pair of struts pivotally connected with said arms with their free ends terminating in wood-engaging means and stops, and a strut locking and tightening device, consisting of a bolt provided with a headed end pivotally engaging one of said struts, with its opposite end provided with a wing-nut and with a collar provided with a stop-lug slidably mounted thereon, said stop-lug being adapted to engage in a slot in the second of the struts aforesaid so as to lock the struts in a biting engagement with the wood of an upright of a scaffold and to increase said biting engagement by further tightening of the nut.

5. A scaffold-bracket comprising a main beam provided with stops, a pair of arms pivotally connected with said main beam, adapted for engagement by said stops, and having their inner ends terminating in wood-engaging means, a pair of struts pivotally connected with said arms with their free ends terminating in wood-engaging means and stops, and means for locking said struts in engagement with the upright of a scaffold.

6. A scaffold bracket comprising a main beam and two oppositely disposed arms pivotally connected therewith and provided with means of engaging a scaffold upright,

said arms being movable into alignment with said beam so as to effect a biting engagement with said upright with the leverage thereby engendered, a pair of struts 5 pivotally connected with said arms and adapted to furnish a bracing support for the same, the free ends of said struts being each provided with a spur integral therewith and means for effecting a permanent 10 biting engagement of said spurs with a scaffold upright.

7. In a scaffold bracket, a main beam, two

oppositely disposed arms pivotally connected therewith and adapted to contact with a scaffold upright on opposite sides, a bracing 15 strut for each arm adapted to engage said scaffold upright, and a locking and tightening device adapted to lock the struts in biting engagement with the upright and to increase said biting effect to any degree desired.

In testimony whereof I have affixed my signature.

DONALD M. MARTIN.
